E. T. SWAINE

UNDERGARMENT

Filed Aug. 7, 1922

UNITED STATES PATENT OFFICE.

EDNA T. SWAINE, OF DES MOINES, IOWA.

UNDERGARMENT.

Application filed August 7, 1922. Serial No. 580,129.

To all whom it may concern:

Be it known that I, EDNA T. SWAINE, a citizen of the United States, and a resident of Des Moines, in the county of Polk and State of Iowa, have invented a certain new and useful Undergarment, of which the following is a specification.

The object of my invention is to provide a one-piece undergarment, which will be 10 form-fitting and which will do away with a two-piece structure, in which case it is ordinarily necessary to have the upper edge of the bloomers overlap the brassière which causes an extra thickness of material right 15 at the waistline.

In this connection, it may be mentioned that when the ordinary bloomers are used, some rubber band or other suitable material is necessary around the waistline for holding 20 the same in position, and it is my object to overcome the undesirable feature of having any surplus clothing or overlapping portions of clothing at the waistline.

Still a further object is to provide a one-piece element, which has a bloomer section and a brassière section sewed together and provided with an open side, which extends from the bottom of the bloomer section to the top of the brassière section, so that the 30 garment may be put on.

Still another object is to provide the edges of the open side of the garment with coacting fastening devices, whereby they may be secured together and to arrange one edge 35 of the bloomers section, so that it substantially overlaps the other edge for keeping them always closed.

With these and other objects in view, my invention consists in the construction, arrangement and combination of the various parts of my undergarment, whereby the objects contemplated are attained, as herein-after more fully set forth, pointed out in my claim, and illustrated in the accompanying 45 drawings, in which:

Figure 1 is a perspective view of my undergarment partially shown open.

Figure 2 is a back view of the garment.

Figure 3 is an enlarged, detail view of a 50 portion of the garment.

Figure 4 is a sectional view taken on the line 4—4 of Figure 1, greatly enlarged; and

Figure 5 is an enlarged, detail view of a portion of the brassière section.

55 In the accompanying drawings, I have used the reference character A to indicate

generally a brassière section and the reference character B a bloomer section.

The brassière section A is provided with a pair of shoulder straps 10. The brassière section is also provided with darts 11, which cause the brassière to be form-fitting and contracted at the lower edge or waistline thereof.

One side of the brassière section is open 65 and a flap 12 is sewed thereon.

Secured to the flap 12 and partially below the material of the brassière section are the eyes 13. On the opposite edge of the brassière section is a binding strip 14 reinforcing the edge of the brassière, so that the hooks 15 may be secured thereto. The hooks 15 may coact with the eyes 13.

The flap 12 overlaps the adjoining edges so as to prevent the hooks and eyes from 75 coming in contact with the person's body.

The bloomer section B includes a pair of leg receiving portions, which are contracted at their lower ends as at 16. A rubber or other suitable elastic band is received within 80 the contracted portion 16, for normally holding the lower ends of the leg portions of the bloomers contracted and in snug fitting position around the leg of the wearer.

The upper edge of the bloomer section B 85 is sewed to the lower edge of the brassière section A and a binder strip 17 is placed on the inner side of the overlapping edges, so as to reinforce and cover the seam between the brassière section and the bloomer 90 section.

The binder strip 17 is so positioned that it comes at the waistline of the entire garment, and I provide an eye 18 on the waistline of the garment, which coacts with a 95 hook 19 for holding the garment snugly around the waistline of the wearer.

Near the upper end of the bloomer section on one side and the back are provided darts 20 for contracting the upper end of 100 the bloomers, so as to make them form-fitting around the waistline and to provide fullness in the leg portions thereof.

The upper edge of the brassière section is provided with a binding 21. 105

One of the leg portions of the bloomer section is open on its side, as at 22. The opening 22 is continuous from the opening in the side of the brassière A.

One edge of the material from the bloomer section projects slightly beyond the edge of the brassière section, so as to form a flap 110

or extension 23, as clearly shown in Figures 1 and 3 of the drawings.

The opposite edge of the bloomer section is arranged substantially flush with one edge of the brassière section.

The flap 23 is provided with a number of fastening devices 24, while the edge of the opposite edge of the bloomer section is provided with coacting snap fasteners 25.

10 It will be seen that one edge of the leg portion of the bloomers laps a substantial distance over the other edge thereof. The purpose of providing the overlapping edge is to prevent there being any open portion 15 between the snap fasteners.

It is desirable to use only a few snap fasteners and for that reason, it is necessary to provide the overlapping edge of some substantial distance.

20 The open side of the garment is arranged preferably on the left side.

It will be seen that the garment is so arranged that it is form-fitting and that there is no fullness at the waistline of the wearer, 25 as is the case when garments are used that are of several pieces.

It will also be seen that the garment is held in proper position by the shoulder

straps and this is quite desirable, especially when the bloomers are comparatively large 30 in the leg portion.

My undergarment is preferably designed for wearing when no corset is used.

Some changes may be made in the form of my undergarment without departing 35 from the essential purpose and spirit of my invention, and it is my intention to cover by my claim, any changes which may be reasonably included therein.

I claim as my invention:

A garment of the class described, comprising a brassière section, form-fitting, with darts at the sides and provided with shoulder straps, a bloomer section sewed thereto at the waist-line, said bloomer section having front and back seams substantially at the vertical center thereof with a closed crotch and having separate legs extending downwardly from the crotch provided at their lower ends with elastic means 50 for causing them to fit snugly, said garment being opened from top to bottom at the side and having fastening means for closing such opening.

Des Moines, Iowa, August 3, 1922.

EDNA T. SWAINE.
